[57] CLAIM

The ornamental design for an amusement toy as shown
and described.

DESCRIPTION

FIG. 1 is a front elevational view of an amusement toy
showing my new design;

FIG. 2 is a rear elevational view thereof;

FIG. 3 is a top plan view thereof;

FIG. 4 is a bottom plan view thereof;

FIG. 5 is a right side elevational view thereof; and

FIG. 6 is a left side elevational view thereof.

The characteristic feature of the claimed design resides
in the specific configuration and ornamentation of the
interior members as shown and described in FIGS. 1, 2,
5, and 6.FIG. 1.

FIG. 2.

FIG. 3.

FIG. 4.

FIG. 5.

FIG. 6.
